F. M. SLATER

ROCK DRILL

Filed June 24, 1925

INVENTOR

Fred M. Slater
BY
Robert G. Ogden
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed June 24, 1925. Serial No. 39,165.

This invention relates to fluid actuated rock drills of the hammer type, but more particularly to valves for drills of said type in which automatic rifle bar rotation is provided for the drill steel.

The objects of the invention are to enable the inlet to the cylinder to be controlled by a sleeve valve encircling the rifle bar while the exhaust from the cylinder is controlled by a separate valve governed by the movement of the piston.

Further objects of the invention will hereinafter appear and the invention is shown in its preferred forms in the accompanying drawings, in which

Figure 1 is a longitudinal sectional elevation of a rock drill partly broken away embodying the invention.

Figure 2 is a similar view showing the parts in a different position, and

Figure 3 is a sectional detail view of a modification of the valve.

The invention is shown applied to a hand held rock drill for purposes of illustration.

Referring to the drawings, the cylinder A is provided with the reciprocating hammer piston B having the fluted forward extension or shank C imparting blows of impact to the drill steel D. The rifle bar E has the rotation ratchet F and ratchet ring G as usual. A handle H is provided for the machine and the parts are held together by the usual side bolts, not shown.

The back head J is provided with the inlet K for pressure fluid entering the chamber L having the passages O and P controlled by the inlet valve Q.

This valve is in the form of a sleeve having the central enlarged head R and the reduced end faces S and T. Passages U and V lead respectively from the valve chamber to the rearward and forward ends of the cylinder. The central head R of the valve operates in a chamber W open to atmosphere through the port X. Kicker ports Y and Z in the cylinder communicate by passages a and b with the chamber W at each side of the valve head R.

The cylinder is provided with the exhaust valve casing c containing the exhaust valve d having the end heads e and f controlling the ports g and h in the cylinder, so that the cylinder may be exhausted through the valve casing to the atmospheric ports j. Small ports k and o connect the ends of the cylin-

der with the ends of the valve casing c for throwing the exhaust valve d in one direction or the other.

The inlet valve Q preferably slides on a sleeve p surrounding the rifle bar E which sleeve is tightly sealed, as shown in the back head J and back bushing J', but if desired, the sleeve p and the valve Q may be formed in one piece as indicated in Figure 3 at q.

The operation of the device is as follows:

Assuming that the piston and valves are in the position indicated in Figure 1, the piston will be moving on its forward stroke.

Live pressure fluid is supplied at the inlet K to the chamber L and passes through the passages P and U around the valve to the rearward end of the cylinder to drive the piston forwardly. The forward end of the cylinder exhausts through the port h and

valve casing c to the atmospheric ports j. Live pressure fluid passing through the port k holds the valve d in its forward position. As the piston passes and uncovers the rearward kicker port Y, pressure fluid under working pressure passes through the passage

a to the rearward face of the head R of the valve Q and throws said valve forwardly to admit pressure fluid through the passages O and V to the forward end of the cylinder

A for driving the piston rearwardly as indicated in Figure 2. When the piston B has covered the exhaust port h at the forward end of the cylinder, the compression due to the forward movement of the piston and also

live pressure fluid acting through the port o will cause the exhaust valve d to move to the position indicated in Figure 2, thus opening the exhaust port g from the rearward end of the cylinder and the valve d will be held in its rearward position by live pressure

fluid.

On the return or rearward stroke of the piston, the valve Q is thrown rearwardly when the kicker port Z is uncovered by the piston and the exhaust valve d is thrown

forwardly due to pressure through the small port k and the cycle is indefinitely repeated.

I claim:

1. In a fluid actuated rock drill of the hammer type, the combination of a cylinder and reciprocating piston, rotation mechanism for the drill steel including a rifle bar, a valve in the form of a sleeve surrounding the rifle bar for controlling the admission of pressure fluid to both ends of the cylin-

105

der, a valve casing located at the side of the cylinder having exhaust ports leading from the ends of the cylinder thereinto, and a reciprocating fluid actuated piston valve located in the said valve casing for controlling the exhaust of motive fluid from the cylinder through the said exhaust ports and valve casing to atmosphere.

2. In a fluid actuated rock drill of the hammer type, the combination of a cylinder and reciprocating piston, a back head for the cylinder and a rifle bar passing through said back head and cooperating with the piston, a sleeve surrounding said rifle bar tightly sealed in the back head, a valve chamber in the back head, an inlet valve in said valve chamber surrounding the rifle bar sleeve and slideable thereon for controlling the alternate admission of pressure fluid to each end of the cylinder, a cylindrical valve chamber at the side of the cylinder, exhaust ports leading from each end of the cylinder to the ends of the said valve chamber, a port leading to atmosphere located in the

said valve chamber and centrally of the ends thereof, and a fluid actuated piston valve adapted to reciprocate in the said valve chamber and to control the said exhaust ports leading from the cylinder.

3. In a fluid actuated rock drill of the hammer type, the combination of a cylinder and reciprocating piston, rotation mechanism for the drill steel including a rifle bar, exhaust means for the cylinder overrun by the piston at each end of its stroke, a valve chamber located at the rearward end of the rock drill coaxial with the longitudinal axis of the cylinder, a stationary sleeve surrounding the rifle bar and sealing the valve chamber from the cylinder, and an inlet valve in said chamber surrounding and sliding on said sleeve, said inlet valve controlling only the admission of pressure fluid to both ends of the cylinder.

In testimony whereof I have signed this specification.

FRED M. SLATER.
